Primary Examiner — Sandra Morris(74) *Attorney, Agent, or Firm* — Paul R Martin(57) **CLAIM**

I claim the ornamental design for an individualized bottle cap, as shown and described.

DESCRIPTION

FIG. 1 is a front, top, and side perspective view of the individualized bottle cap embodying the design of the present invention.

FIG. 2 is a top plan view of the individualized bottle cap. FIG. 3 is a front elevational view of the individualized bottle cap.

FIG. 4 is a rear elevational view of the individualized bottle cap.

FIG. 5 is a side elevational view of the individualized bottle cap; and,

FIG. 6 is a side elevational view of the individualized bottle cap as seen from the side opposite to the side shown in FIG. 5.
